CLAIM

The ornamental design for a vehicle roof, as shown and described.

DESCRIPTION

FIG. 1 is a perspective view of a vehicle roof embodying our new design;

FIG. 2 is a top plan view thereof;

FIG. 3 is a right side elevation view thereof;

FIG. 4 is a left side elevation view thereof;

FIG. 5 is a front elevation view thereof; and,

FIG. 6 is a rear elevation view thereof.

The broken lines in the drawings illustrate portions of the vehicle roof that form no part of the claimed design.
